FUEL FEED DEVICE FOR OIL BURNERS

Filed Dec. 22, 1945

UNITED STATES PATENT OFFICE

2,492,516

FUEL FEED DEVICE FOR OIL BURNERS

Albert H. Berger, Rocky River, Ohio, assignor, by
mesne assignments, to The Consolidated Iron-
Steel Manufacturing Company, Cleveland,
Ohio, a corporation of Ohio

Application December 22, 1945, Serial No. 636,623

1 Claim. (Cl. 158—87)

1

The invention relates to oil stoves, and more specifically to oil burner mechanisms of the type comprising a burner, fuel supply means, and valve means controlling the fuel flow to the burner.

An object of the invention is to provide novel burner mechanism of simple and sturdy construction, the parts being economically manufacturable from readily available materials.

Other objects and advantages will be apparent from a study of the following description in conjunction with the accompanying drawings in which:

Fig. 1 is a view in front elevation of a fragmentary portion of an oil stove embodying my invention;

Fig. 2 is an enlarged sectional view taken from the plane 2—2 of Fig. 1;

Fig. 3 is a detail view of a portion of the apparatus shown in Fig. 2; and shown in modified form;

Fig. 4 is a sectional view taken from the plane 4—4 of Fig. 3;

Fig. 5 is a bottom plan view taken from the plane 5—5 of Fig. 2.

Before the present invention here illustrated is described in detail, it is to be understood that the invention here involved is not limited to the details of construction or the specific arrangement of parts herein illustrated or described, as the invention obviously may take various forms. It also is to be understood that the phraseology or terminology herein employed is for the purpose of description and not of limitation, the scope of the present invention being defined in the appended claim.

Speaking first generally, with reference to Fig. 1, I show a fragmentary portion of a stove, designed for liquid fuel consumption, such fuel being hereinafter identified by the term "oil." The stove may rest on any suitable support (not here shown) such as a utility cabinet or conventional legs. The stove includes top, bottom, and side members, herein identified by reference characters 12, 13 and 14 respectively. The stove further includes an oil level bowl 15, an oil container 16, a burner 17, and an oil supply pipe 18 for maintaining liquid communication between the oil level bowl and the burner. Oil feed to the burner is controlled by valve means under control of a manually operable knob 19. It will be understood by those familiar with stoves of this character that a fixed oil level is automatically maintained in bowl 15 at or about the dotted line L by a liquid seal arrangement not here necessary to describe or show, and that when the burner is

in operation, the oil rises to the same level in the burner, as will later appear.

The special and novel construction of the burner and associated fuel feed and control parts will now be described.

The burner base 20 may be pressed or drawn from a circular sheet metal blank. It has a generally flat central portion 21 and a depending annular channel or trough 22 which is adapted to hold oil up to a level established by the corresponding level in the bowl 15. The upwardly extending walls of the trough 22 are out-turned at 23 to provide a pair of horizontal annular shoulders which support a chimney arrangement 24, as indicated in dotted line in Fig. 1. It will be understood that an annular wick is carried in trough 22 and that the lower edge of the wick is immersed in the fuel oil. The oil is conveyed from supply pipe 18 to trough 22 as follows. Referring especially to Figs. 2 and 3, a tubular housing 25 has a plug 26 inserted in the end thereof, preferably, and most conveniently, by means of a press fit. The plug is provided with a longitudinal bore 27. The outer end of the plug extends slightly beyond the end of the housing, and is reduced in size at 28 to have a forced fit in an aperture 29 in the side of fuel pipe 18. The inner end of the wall of bore 27 is threaded to receive a complementary external thread on a needle valve stem 30 of a valve manipulating rod 30a. A valve needle 31 on the inner end of the valve stem cooperates with a valve seat 32 carried by the wall of bore 27. It will be apparent that rotary motion of knob 19 either establishes or interrupts communication between fuel pipe 18 and bore 27.

Burner 17 is placed in liquid communication with bore 27 as follows: A transverse groove 33 is cut in the wall of housing 25, and extends part way into the annular wall of plug 26. Preferably the groove conforms generally in contour with the bottom wall of the burner base, so that the said bottom wall may be nested in the groove. A permanent assembly is assured by brazing adjacent wall portions of trough and housing, as indicated at 35 in Fig. 2, thereby effecting a leak-proof connection. The lower trough wall, and the plug 26 are pierced at 36 so as to permit oil to flow upwardly into trough 22 when the valve is open. A brazed connection at 31 is also established at the location where the housing 25 abuts against fuel pipe 18. The reduced diameter portion 28 provides a shoulder, and as shown in Fig. 2, the end of the tubular housing 25 is turned inwardly over the shoulder so that the end of the tubular housing 25 abuts the fuel pipe 18 as stated; or

if preferred, as in Fig. 3, the end of the tubular housing is not turned inwardly. The upwardly inclined position of housing 25 has been established as most convenient from the standpoint of assembly and manipulation, but of course the housing can be disposed horizontally or even downwardly, provided that the valve stem be suitably packed to prevent oil leakage. No leakage is possible as long as the upward inclination places the upper end of housing 25 above the prevailing oil level. It will be understood that the weight of the burner, wick and chimney, not shown, will be supported on housing 25, by the brazed connection 35. This is rendered possible by the light sheet metal construction of the burner and chimney.

The advantages of the above described novel structure will now be apparent. The burner itself can be drawn from a single blank of sheet metal. The housing 25, plug 26, and valve stem 30 are all made from readily available materials. The housing and stem can be formed from cold rolled steel. For the plug 26, I prefer a cuprous alloy such as brass. The brazing operation gives a more firm and reliable union than does soldering, and a brazed joint is not so susceptible to failure from a possible rise in temperature, or from other causes.

Other novel features of construction of those portions of the oil stove herein disclosed are covered by my copending applications, Serial Numbers 636,625; 636,626; 636,627; filed concurrently herewith.

What I claim is:

In an oil burner and associated structure of the class described, a burner base having an upwardly open wick trough; a fuel supply pipe having a portion below the trough and provided with a circular aperture through a side thereof; a valve housing in the form of a piece of tube open at an end thereof; the open end of the tube abutting directly upon the side of the fuel pipe portion, and extending therefrom in an upwardly inclined

direction; an elongated plug telescoped into the tube interior and provided with a cylindrical end portion of reduced diameter, projecting from the said end of the tube and having a press fit in the circular aperture of the fuel pipe; the end of the tube sealingly joined to the side of the pipe where it abuts thereon; the plug having a bore therethrough opening at one end through its cylindrical end portion into the fuel pipe, and outwardly thereof being of enlarged diameter to provide a valve seat; a rod-like needle valve having a stem threaded in the enlarged diameter portion of the plug bore, and an elongated valve needle extending therefrom toward the valve seat, and the valve stem extending outwardly through and beyond the other end of the tube and provided with a handle for rotating the stem to screwingly move the valve needle toward and from the valve seat; an upwardly open transverse groove in the upper side of the tube and the side of the plug therein; the underside of the wick trough being disposed in the groove and sealingly joined to the wall of the groove; an oil duct communicating between the wick trough and the plug bore at a point opposite to the elongated valve needle.

ALBERT H. BERGER.
